Primary Examiner — Elizabeth Albert(74) *Attorney, Agent, or Firm* — Superior IP, PLLC;
Dustin L. Call(57) **CLAIM**

The ornamental design for a UV pen, as shown and described.

DESCRIPTION

FIG. 1 is a top view of a UV pen;

FIG. 2 is a bottom view thereof;

FIG. 3 is a rear view thereof;

FIG. 4 is a front view thereof;

FIG. 5 is a right side view thereof;

FIG. 6 is a left side view thereof; and,

FIG. 7 is left rear perspective view thereof.

The broken lines in the drawings are included to show portions of the UV pen that form no part of the claimed design.
